UNITED STATES PATENT OFFICE

158,730

WHEEL BALANCER

Arthur Fuller Dean, Glenview, and David C. Peterson, Chicago, Ill., assignors to Stewart-Warner Corporation, Chicago, Ill., a corporation of Virginia

Application March 10, 1949, Serial No. 1,325

Term of patent 14 years

(Cl. 52—2)

To all whom it may concern:

Be it known that we, Arthur Fuller Dean and David C. Peterson, citizens of the United States, residing at Glenview and Chicago, respectively, in the county of Cook and State of Illinois, have invented a new, original, and ornamental Design for a Wheel Balancer, of which the following is a specification, reference being had to the accompanying drawing, forming part thereof.

Fig. 1 is a perspective view, showing the rear and side; and

Fig. 2 is a perspective view showing the front and other side of a wheel balancer showing our new design.

We claim:

The ornamental design for a wheel balancer, substantially as shown.

ARTHUR FULLER DEAN.
DAVID C. PETERSON.
